UNITED STATES PATENT OFFICE.

WILLIAM HUGO MATTHIES, OF ANTWERP, BELGIUM, ASSIGNOR, BY MESNE ASSIGNMENTS, TO WESTERN ELECTRIC COMPANY, INCORPORATED, A CORPORATION OF NEW YORK.

MACHINE TELEPHONE SWITCHING SYSTEM.

1,197,048.

Specification of Letters Patent.

Patented Sept. 5, 1916.

Application filed July 20, 1914. Serial No. 851,860.

To all whom it may concern:

Be it known that I, WILLIAM HUGO MATTHIES, a resident of Antwerp, Kingdom of Belgium, have invented certain new and useful Improvements in Machine Telephone Switching Systems, of which the following is a full, clear, concise, and exact description.

This invention relates to improvements in machine telephone switching systems, and particularly to systems in which automatic switching apparatus is adapted to extend or control the extension of a desired connection by means of impulses sent from a distant station.

More specifically, the invention relates to impulse or controlling circuits and provides a new and improved system and apparatus whereby impulses delivered from a distant station will be received and caused to produce the necessary results to extend the connection to the desired line.

A particular feature of the invention has to do with the relay system provided at the incoming end of an impulse circuit of this character, such relay system being simple and efficient and involving but a single slow acting relay. Most specifically this relay system involves a single relay located in the impulse circuit controlling two other relays associated therewith, one of the said relays being a slow acting relay; such relay system controlling the stepping of the necessary switches in response to numerical impulses in such impulse circuit; controlling the changeover from one of such switches to be set to another in response to a definite impulse in said circuit and also controlling the disconnection and restoration of the circuits and the apparatus, if the line circuit is open at the sending station for a relatively long period, as in the case of a calling subscriber in a full automatic exchange system replacing his receiver upon the hook.

Figures 1 and 2 of the drawings taken together show one embodiment of the invention.

This invention is illustrated herein as forming a part of a full automatic telephone exchange system of the type in which a register-controller equipment receives impulses from a calling substation to set the various register controllers which control the selector switches by which the circuit

is extended to the desired line, the set position of the selector switches being determined by the set position of the register controllers referred to. It will be understood, of course, that the specific features herein shown, and particularly the features relating to the impulse circuit and its associated relay system, are not confined to systems of this type, but may be used in systems widely varying in character, either of the full-automatic type wherein the subscriber operates the sending mechanism, or of the semi-automatic type wherein an operator at an exchange controls such sending mechanism.

Systems somewhat of the type herein illustrated are described in the British patent specification No. 26,079 of 1910 and No. 21,259 of 1911.

The invention will be best understood, and the features thereof best appear from the description of one form thereof as illustrated in the accompanying drawings. The system illustrated in the drawings is for convenience shown as a one-hundred line system in which an established connection includes a line finder switch which searches for and seizes the calling line to connect it to a connecting circuit. The finder switch has associated therewith a connecting circuit, including the usual source of current, situated in association with the usual repeating coil, as well as a registering and controlling equipment, and a selector switch adapted to select, test and connect with the desired line of the 100 lines to which it has access. It should be understood, of course, that the invention is not limited to systems of this size, nor to any of the specific features disclosed herein. For example, the system may be extended to any size by the insertion of group selectors in the circuit in the well known manner, and the addition of further register controllers in the registering and controlling equipment corresponding to such group selectors. Also it is not necessary that the registering and controlling equipment should be permanently associated with the connecting circuit as shown, but may be common to a number of connecting circuits and connected to a particular one thereof when necessary in any well known manner.

Of the apparatus diagrammatically shown in the drawings, the line finders, selector switches, and sequence switches are of types

well known in the art, such switches being illustrated as power driven switches, the specific features of which will sufficiently appear from the description of the operation thereof.

The register-controllers diagrammatically illustrated may be of any desired mechanical structure which performs the functions hereinafter to be described. For example, they 10 may be of the type shown in Fig. 1 of the British patent specification No. 26,079 of 1910.

The system shown will best be understood from the description of the operation 15 thereof.

Assume that the subscriber at station 41 illustrated to the left of the drawing desires connection with the subscriber at station 42 illustrated to the right thereof, the 20 line of which latter subscriber may be designated for example as line 42. The subscriber 41 will, to initiate the call, remove his receiver from its switch hook, thereby closing his line circuit and energizing the 25 line relay 43 individual to his line in the usual manner. A circuit is thereupon closed through the relay 44, and the resistances 45 and 46, energizing such relay and placing a selectable potential upon the test terminal 30 47 of the calling line wherever the same appears in the line finder switches having access thereto. The number of such line finder switches, and associated connecting circuits is determined by the traffic in the exchange 35 and may represent the number of simultaneous calls which must be provided for in the system. The energization of the relay 44 closes the circuit to the power magnet 52 of all of such line finders as may be 40 idle at this time, such circuit including the springs 26 top and 25 bottom of the sequence switch 20 individual to each line finder and its connecting circuit. All such idle line finders will therefore move to search for 45 the calling line until the brush 48 of one of them comes in contact with terminal 47 upon which such selectable potential exists and a circuit is established including the high resistance winding of relay 50, the 50 springs 29 top and 27 and the interrupter brush 49 of this line finder. This will cause the energization of the relay 50 which attracts its armature and closes a circuit through its low resistance winding over the 55 spring 28 bottom in shunt of the high resistance winding of such relay. This so reduces the potential upon the test terminal 47 of the calling line in all of the other line finders, that no other line finder bringing its brush 48 in contact therewith will 60 have its relay 50 energized and therefore prevents the seizure of this line by any other such line finder. As the line finder which has first brought its brush 48 in contact 65 with the terminal 47 moves so that its

brushes are centered upon terminals of the calling line, the interrupter circuit opens at the interrupter brush 49, and the relay 51 is energized in series with the relay 50 over spring 31. The energization of relay 51 70 opens the circuit of power magnet 52 of the line finder at the same time closing over spring 23 bottom the circuit of the holding magnet 53 of such line finder thereby bringing the line finder positively to rest with 75 its brushes centered upon the terminals of the calling line. At the same time the energization of relay 51 closes a circuit to drive the sequence switch 20 out of its first position and such sequence switch under control of the spring 21 will move into its fourth position. On coming into its second position the sequence switch closes the spring 30 top, which causes the energization of the cut-off relay 54 of the calling line. This 80 relay opens the circuit of the line relay 43 and maintains the calling line busy, in all the line finders and selector switches in which it appears, in the usual manner, independent of the relays 50 and 51, the circuit of which is opened at the spring 29 top as the sequence switch 20 leaves its second position. As the sequence switch 20 comes into its second position the impulse circuit extending from the calling sub-sta- 85 tion to the register-controller equipment is completed at the springs 33 bottom and 34 top and such circuit is supplied with current from the battery shown between the repeating coil terminals. This circuit will 90 be maintained in the third and fourth position, and also in the fifth, sixth, and seventh positions of the sequence switch 20. The closure of this circuit energizes the stepping relay 91, which by the closure of 95 the circuit including the spring 82 and the register sequence switch 80 drives this sequence switch into its second position. It should here be noted that the respective sequence switch springs are not shown as 100 associated with the power magnet thereof, but are so shown as to present as clearly as possible circuits which they control. It should be understood, however, that all the sequence switch springs indicated in Fig. 1 are as- 105 110 sociated with and form a part of the connecting circuit sequence switch 20, whereas those shown in Fig. 2 are associated with and form a part of the register sequence switch 80. It will, of course, be further understood 115 120 that each of the sequence switch springs is closed and only closed in the positions indicated adjacent thereto. The register sequence switch 80 being in position 2, and the connecting circuit sequence switch 20 being 125 130 in position 3 or 4, the impulse circuit and the register-controlling equipment are now ready for the sending of the controlling impulses by the subscriber.

The subscriber's impulse sending device is 130

herein illustrated diagrammatically at 55. It will, of course, be understood that this impulse sending device may be of any type well known to the art, it being sufficient for 5 this description to state that such impulse device is operated to produce a number of short breaks in the circuit corresponding to the several digits of a numerical designation of the line the subscriber desires. Having 10 assumed, therefore, that the number of the line desired by the subscriber is 42, the calling subscriber will first produce at his impulse sending device 55, a series of five interruptions of the impulse sending circuits, 15 such interruptions being separated each from the other by a relatively short closure of the circuit in the usual manner. The sending of the digit 4 requires 5 impulses for the reason that the digit zero requires 20 one; the digit 1 requires 2, and digit 2 requires 3, and so forth. At each interruption of the circuit the relay 91 is deenergized, but the first time such relay is deenergized it closes the circuit which includes spring 25 89 for energizing relay 92 which remains energized and locked up over its left-hand winding. The energization of the relay 92 prepares at its right armature a circuit for the stepping magnet 76 of the tens register 30 controller 77 which is energized upon a subsequent energization of the relay 91. At the end of this first short interruption of the sending circuit, relay 91 will be again energized, and the relay 92 remaining locked 35 up, a circuit will be established over the springs 83 bottom and 84 bottom, and right armature of the relay 92 to energize the stepping magnet 76 of the tens register controller which will thereby cause the movement 40 of the register disk one step from normal in a clockwise direction. The relay 93 will not be energized at this time, the circuit interruption and the closure between two impulses being too short to allow the relay 45 91 to remain energized or deenergized long enough to cause the relay 93 to respond, such relay being of the slow acting type. Upon the deenergization of the relay 91 at the second impulse the magnet 76 is deenergized 50 to prepare for a second step. Upon the subsequent closure of the sending circuit and the energization of the relay 91, the tens register controller disk will be given a second step. This will continue until at the 55 end of the fifth break the disk of the tens register controller 77 has been given 5 steps in a clockwise direction. At this time the circuit will be maintained closed for a relatively longer interval, that is, at least for the time required for the subscriber to initiate a second operation of his impulse sender to send the units impulses. This period will be sufficiently long for the circuit, including the magnet 76 of the tens 60 register controller, to energize the slow act- 65 ing relay 93 over its left-hand winding. Upon energizing this relay closes the circuit to drive the sequence switch 80 out of position 2, and such sequence switch under control of spring 81 will move into position 4. 70 In moving through position 3, however, this sequence switch has opened the spring 89 thereby causing the deenergization of the relay 92. The circuit of the relay 93 is therefore open not only at the springs 83 75 and 84 bottom but also at the right hand armature of the relay 92, and such relay 93 will therefore deenergized when the sequence switch 80 reaches its fourth position. The register controlling equipment now 80 awaits the sending of the second series of impulses indicating the unit digits of the desired line. As in the former case the first deenergizing of the relay 91 causes the energization of the relay 92 which again locks 85 itself up through its left-hand winding, and prepares the circuit for the stepping magnet of the register controller, this time, however, for the stepping magnet 96 of the units register controller, this circuit also 90 being prepared by the closure of the springs 83 top and 84 top. Upon the subsequent energization of the relay 91 the stepping magnet 96 moves the disk of the units register controller 97 one step from normal in 95 a clockwise direction. Here again both the impulses and the periods between impulses allow the energization or deenergization of the stepping relay 91 for an insufficient time to cause the energization of the relay 93. 100 Consequently for each impulse the disk 97 of the units register controller will be moved one step from normal in a clockwise direction. At the end of the third impulse, however, in the case assumed the circuit will be 105 closed for a longer period, and the slow acting relay 93 will be energized and close the circuit to move the sequence switch 80 from its fourth into its sixth position. As the sequence switch 80, however, moves out 110 of its fourth position, springs 83, 84, and 89 are opened, and the relay 93 will be deenergized, since relay 91 is now maintained continuously energized except in case of the 115 premature disconnection by the calling subscriber, which will be hereinafter considered. The register sequence switch 80 will therefore remain in its sixth position, in which position the tens selection controlling operation in the selector switch shown will take 120 place.

In position 6 of the register sequence switch 80 the fundamental or selection controlling circuit will be closed at the spring 87 and the back contact of the relay 95 to 125 energize the line relay 56 of the selector switch, and stepping relay 94 of the registering and controlling equipment. Relay 56 energizing drives the sequence switch 20 into its fifth position over a circuit including 130

- spring 24 bottom. In the 5th position of the sequence switch 20, the relay 56 being maintained energized, circuit is closed for the tripping spindle power magnet 57 over 5 the spring 35 top and such tripping spindle moves to bring the projections thereon successively into position to trip the various sets of brushes on the brush carriage of the group selector in the well-known manner.
- 10 As the tripping spindle moves each step or stage that part of the fundamental circuit including the stepping relay 94 is shunted (ground, 69, 38, 94, 87, ground) and causes the deenergization of such relay while line 15 relay 56 is maintained energized. Of course as the respective projections on the tripping spindle are brought into proper position to trip the corresponding set of brushes, the shunting circuit is opened in the well-under- 20 stood manner.
- When the fundamental circuit was first closed stepping relay 94 closed at its front contact a circuit over spring 85 bottom to energize the restoring magnet 78 of the tens 25 register-controller 77. This caused the disk of the tens register controller to move one, step in a restoring direction, that is, the counter-clockwise direction, and upon the deenergization of the restoring magnet 94 the stepping relay 78 is deenergized to prepare 30 for a second step in such direction. Obviously each time that the stepping relay 94 is energized and deenergized the disk of the register controller 77 will take a further 35 counter-clockwise step. When, however, the disk of the tens register controller has taken five steps in a counter-clockwise direction *i. e.*, when disk 77 reaches its normal position, the contact 79 will be closed, and when 40 the relay 94 is deenergized by the closing of the shunt at the tripping spindle, circuit is closed from grounded battery through such spring 79, sequence switch spring 86 top, the winding of relay 95, and the back contact 45 tact and armature of relay 94 to ground, to energize the cut-off relay 95 which opens the fundamental circuit and at the same time drives the sequence switch 80 out of its 6th position. The opening of the fundamental 50 circuit by the cut-off relay 95 took place on the 5th deenergization of the stepping relay 94, that is, as the tripping spindle closed for the fifth time the shunt of the fundamental circuit, which closure took place as the pro- 55 jection of such tripping spindle adapted to release the fifth set of brushes upon the brush carriage was coming into position wherein subsequently such set of brushes would be released. The fundamental circuit 60 being open as the tripping spindle comes fully into such position, both circuits for the line relay 56 are opened and, such relay being deenergized, the tripping spindle is brought to a stop and the sequence switch 20 is driven by a circuit including spring 24 top into its 6th position.
- As the sequence switch 80 reaches its 8th position the sequence switch 20 is already in its 6th position and the fundamental circuit is again closed by the spring 87 to energize the stepping relay 94 and the line relay 56. The energization of the stepping relay 94 causes the first step of the disk of the units register controller 97 over a circuit including spring 85 top in the usual manner. The energization of the line relay 56 drives the sequence switch 20 into its 7th position. In this position such relay being maintained energized a circuit is closed over spring 36 to energize the brush carriage power magnet 59 and the brush carriage will start in motion. In the first portion of this motion the proper set of brushes, that is, the fifth set, coöperating with sets of terminals of lines numbered from 40 to 49 will be released by the tripping spindle. Subsequently as the released brushes come into co-operative relation with the sets of contacts the interrupter 60 causes the intermittent closure of the contact 62. The closure of this contact takes place each time as the brushes are about to come in contact with the respective set of terminals with which they coöperate; the contact 62 being closed once for each set of terminals with which the brushes make connection, being open only when the brushes are properly centered upon such terminals. Therefore, before the brushes come in contact with the first set of terminals the contact 62 of the interrupter 100 will once have closed a shunt for that portion of the fundamental circuit including the stepping relay 94 to deenergize such relay. As the brushes come squarely in contact with the first set of terminals this shunt will be 105 opened and the relay 94 will be again energized to produce a second step in a counter-clockwise direction by the disk of the units register controller unless such disk is already in its normal position. As, however, the disk has been set three steps in a clockwise direction the relay 94 will be energized three times before, on its third deenergization, a circuit is found closed for the cut-off 110 relay 95 including the springs 86 bottom and 99. When this occurs the selected brushes of the selector are in contact with the third set of contacts in the selected bank. The energization of the cut-off relay 95 has opened the fundamental circuit at the back contact 115 of its armature and has driven the sequence switch 80 out of its 8th position and into its 9th position, in which position the fundamental circuit is opened at spring 87. When the circuit through the interrupter contact 120 62 is now opened as the selected brushes come squarely in contact with the third set of contacts on the selected level, that is, cor-

tacts of the line No. 42 (the desired line) no circuit will exist for the line relay 56, and such relay deenergizing opens the circuit of the power magnet 59 and closes a circuit over 5 spring 37 top for the holding magnet 63 of the selector brush carriage, thereby bringing such brush carriage positively to a stop with the selected brushes accurately centered upon the terminals of the desired line. The de- 10 energization of the line relay 56 at this time also drives the sequence switch 20 out of its 7th and into its 11th position.

Before considering what occurs in the selector apparatus as the sequence switch 20 15 leaves its 7th position, it will be observed that the sequence switch 80 on coming into its 9th position closes a circuit for the relay 95 over spring 86 top which includes the normal contact 79 of the tens register controller 20 so that relay 95 energizes and drives the sequence switch 80 into its 10th position. In the 10th position a circuit is closed for this same relay over the spring 86 bottom and the normal contact 99 of the units register controller 25 to energize such relay to drive sequence switch 80 into its first or normal position. It will be observed that if either the tens register controller or the units register controller had for any reason been left 30 out of its normal position, as, for example, in case of premature disconnection, which will be hereinafter described, it would be restored to normal position in the 9th and 10th positions respectively of the sequence switch 80. 35 Assuming that the tens register controller was off normal when this sequence switch reached its 9th position the circuit described for energizing the relay 95 would not have been closed but a circuit would have been 40 closed for the restoring magnet 78 of such tens register controller including spring 85 bottom and spring 90, which would include the interrupter 75, and the restoring magnet 78 would have been intermittently energized 45 until the tens register controller is again in its normal position, when the relay 95, being energized, the sequence switch 80 would move out of its 9th position. Correspondingly, if the units register controller 50 was off normal the restoring magnet 98 thereof would be intermittently energized over a circuit including the interrupter until upon the energization of the relay 95, when the spring 99 is closed as its register controller 55 comes into its normal position, the sequence switch 80 is driven from its 10th position into normal position. During the movement of the sequence switch 20 through its 10th position, the test of the desired line 60 on the terminals of which the selected brushes now rest is made by the relays 50 and 51. If the desired line is idle full potential of the battery connected to the cut-off relay 65 thereof will appear upon the test

terminal thereof. This will be sufficient to 65 energize the test relay 50 through its high resistance left hand winding so that it attracts its armature and closes a parallel path for itself through the spring 28 top and its low resistance right-hand winding. It 70 should be observed that the test circuit includes the front contact of the calling supervisory relay 64 so that in case of a premature disconnection the selector switch will not seize the desired line in the manner to 75 be described, but the operations thereof will proceed in the same manner as though the desired line had been found busy. The calling supervisory relay 64 is energized at this time in a normal call by the battery shown 80 between the terminals of the repeating coil, springs 33 bottom and 34 top having been opened and the springs 33 top and 34 bottom closed upon the completion of units selection to include the left-hand branches of 85 the repeating coil in the circuit of the calling subscriber's line. As long, therefore, as the circuit is closed at the calling subscriber's sub-station the calling supervisory relay 64 will be maintained energized. On the test 90 of the desired line in position 10 as soon as the relay 50 was energized upon such line being found idle, the closure of the low resistance path through the right-hand winding of such relay so reduces the potential 95 upon the test terminal of the desired line that no other selector switch testing such line would find sufficient potential upon the test terminal thereof to cause the energization of its test relay 50. At the same time that the relay 50 is energized the cut-off relay 65 of the desired line is energized to prevent the energization of the line relay thereof when the called subscriber answers. Therefore, when such subscriber does answer no selectable 100 potential will be placed upon the test terminal of such line, corresponding to the test terminal 47 of the calling line, in the line finders where such line appears. Assuming that the desired line is found idle, as the sequence 105 110 switch 20 reaches the 11th position the relay 51 which has been energized with the relay 50 will be maintained energized by the circuit including the armature of such relay 50 and the spring 28 top in spite of 115 the fact that the spring 29 bottom is open. A circuit will therefore be closed over spring 26 bottom to drive the sequence switch 20 through its 11th position and into its 12th position.

The 12th position of the sequence switch 20 is the ringing position. In this position ringing current the source of which is indicated adjacent to the ringing relay 66, will pass through such relay and spring 39 top 125 and thence be projected over the called subscriber's line, finding ground over spring 40 bottom. So long as the called subscriber's

circuit is maintained open to direct current, his receiver being upon its hook, insufficient ringing current will pass through relay 66 to energize such relay. When, however, the 5 called subscriber answers the circuit to direct current will be closed at the substation, and sufficient ringing current will pass through relay 66 to energize such relay, and circuit is closed to drive the sequence switch 10 20 out of its 12th position and into its 14th position. This is the talking position of the sequence switch 20, and the springs 39 bottom and 40 top being closed, talking connection is now extended from the calling 15 subscriber 41 to the called subscriber 42. Conversation may now take place.

Disconnection.—Disconnection in the system shown is under the control of the calling subscriber, but, in case the called subscriber 20 should not immediately replace his receiver on its switch hook after the calling subscriber has done so, means are provided whereby the called subscriber's line will take upon itself the character of a calling line 25 and thereby engage and make busy some other line finder and its associated connected circuit. Upon the opening of the circuit at the calling subscriber's substation the calling supervisory relay 64 will be deenergized. 30 This will drive the sequence switch 20 out of its 14th and through its 15th positions into its 16th position by a circuit including the spring 22 top. In the 16th position the sequence switch awaits the opening of the 35 circuit of the called subscriber's substation, which, as soon as it occurs, causes the deenergization of the called supervisory relay 67 and drives the sequence switch 20 out of its 16th position and into its 17th position 40 over a circuit including spring 30 bottom.

It should be noted that as the sequence switch left its 15th position the opening of the springs 30 top, 33 top and 34 bottom rendered the calling subscriber's line free to 45 subsequently call or be called and be connected to by any selector or by any idle line finder of the group in which it appears. As the sequence switch 20 came into its 17th position the closure of the spring 23 top 50 makes a test to determine whether the registering and controlling equipment is again in normal condition. If such is the case, that is, if the sequence switch 80 is now in position 1 a circuit is closed over springs 74 bottom and 23 top to drive the sequence 55 switch 20 into its 18th position. In this position the brush carriage power magnet 59 is energized over a circuit including the spring 25 top, back contact of relay 51, spring 26 bottom and back contact of relay 56. The brush carriage now restores, the 60 released brushes being restored in the usual manner in such movement. When the brush carriage reaches its normal position the interrupter brush 60 comes in contact with the normal plate of the interrupter mechanism 61 and a circuit is established over the spring 38 bottom to energize the relay 56, which, by attracting its armature, opens the circuit of the power magnet 59 and closes 70 a circuit over spring 37 bottom to the holding magnet, bringing the brush carriage positively to a stop in its normal position. At the same time relay 56 closes a circuit over spring 24 bottom to drive the sequence 75 switch 20 into its normal position. As the tripping spindle has been restored by a circuit including the spring 35 bottom in the 16th, 17th or 18th positions of the sequence switch 20 all of the apparatus which has 80 been used is again in its normal position.

Attempted connection to a busy line.—If when the sequence switch 20 was passing through its 10th position the line desired had been busy, the normal potential upon 85 the test terminal thereof in the selector would have been reduced either by the connection of some other selector switch and the connection of a low resistance circuit through the right-hand winding of the test 90 relay 50 thereof to such test terminal if such line were busy as a called line, or by the connection of a circuit including the spring 30 top to the test conductor leading to the cut-off relay thereof if such line had been 95 busy as a calling line. Insufficient current would, therefore, have passed through the high resistance left-hand winding of the relay 50 of the testing selector, and such relay would not have been energized. Therefore, 100 when the sequence switch 20 came into its 11th position, no circuit would exist for the relay 51 and such relay not being energized in such position the sequence switch 20 would stop. The un-energized condition of 105 the relay 51 in this position would cause the restoration of the selector switch to normal, a circuit being closed for the power magnet 59 thereof through the spring 25 top, back contact of relay 51, spring 26 bottom and 110 back contact of relay 56. The brush carriage would therefore be restored to normal precisely in the manner hereinbefore described, and, on reaching its normal position, relay 56 would be energized to stop 115 such brush carriage and to drive the sequence switch 20 out of its 11th position through its 12th and 14th positions and into its 15th position, where it would stop. The 15th position is the busy back position. In this position 120 a busy tone is applied to the circuit of the calling subscriber's line over the spring 32 and the calling subscriber would thereby be apprised that the desired line is busy. He then replaces his receiver upon its switch 125 hook, opening the circuit at his substation, and causes the deenergization of the calling supervisory relay 64. This closes a circuit to drive the sequence switch 20 out of its 130 15th position. As the called supervisory re-

lay 67 is at this time deenergized the sequence switch will be moved into its 17th position. It being assumed that the register controlling equipment is again in normal position 6 the sequence switch will continue to move into its 18th position. The selector switch being in its normal position a circuit will be established for the relay 56, which, on energizing, drives the sequence switch 20 into 10 its first or normal position, and all the apparatus is again in normal condition.

Premature disconnection.—If the called subscriber should not answer in response to the ringing current projected upon his line 15 in the 12th position of the sequence switch 20, the calling subscriber may produce restoration by merely replacing his receiver upon its hook. This is accomplished by the deenergization of the relay 64 in the 12th or 20 ringing position, which closes circuit over spring 22 top, to drive the sequence switch directly into its 16th position, where restoration will take place in the normal manner, the called supervisory relay 67 being already 25 retracted. If the calling subscriber should replace his receiver during the 11th position, the apparatus would move in the normal manner into the 12th position of the sequence switch 20, when restoration would take place 30 as described. If the calling subscriber should replace his receiver during the 8th or 9th or 10th positions of the sequence switch 20 the circuit for the relay 51 would not be closed either at the spring 31 or the 35 front contact of the calling supervisory relay 64, and therefore neither the relay 50 nor the relay 51 would be energized in the 10th position and the same condition would exist as though the called line were busy, the selector switch restoring to its normal position 40 in the 11th position and the sequence switch moving on into its 15th position. It would not stop in this position, however, as the circuit is closed therefor over spring 22 top 45 and the back contact of relay 64, and the apparatus would be restored to normal in the manner hereinbefore described. If the calling subscriber should restore his receiver to its hook at any time while the sequence 50 switch 20 is in positions 2 to 7 the stepping relay 91 is deenergized for a relatively long period, thereby causing the energization of the slow relay 93 by a circuit including spring 88, and the back contact of such relay 55 91. The relay 93 on being energized, closes a circuit to drive the sequence switch 80 directly into its 9th position.

In the 9th position of the sequence switch 80 the spring 74 is closed to drive the 60 sequence switch 20 into its 8th position, where the restoration of the sequence switch 20, the selector switch (if it had been moved from normal) and the apparatus associated therewith would take place in the manner 65 hereinbefore described. In the 9th position

of the sequence switch 80 if the tens register-controller is in normal position, either in the event that it has not been moved from normal or that it has been restored to normal in the normal operation of the system, 70 the sequence switch moves to its 10th position, where a corresponding test would be made of the position of the units register-controller, which, if it is found in its normal position causes the movement of the 75 sequence switch 80 into its normal position. In case either the disk of the tens register controller 77 or the units disk of the register controller 97 had been off normal such disks would have been restored in the 9th 80 or 10th position of the sequence switch respectively in the manner hereinbefore described. It will be observed that in case of premature disconnection of this character, if both the tens register-controller and the 85 units-register controller were off normal it might be that the sequence switch 20 would reach its 17th position before the restoration of the register controller disks had been completed. In this case the sequence switch 90 20 would remain in its 17th position as the circuit therefor from the spring 23 top is opened at the spring 74 bottom of the sequence switch 80. When, however, the register controlling apparatus is again in 95 its normal position the spring 74 bottom will be closed and the sequence switch 20 will move into its 18th position, from whence it will be moved in the normal manner into its normal position, if the 100 selector switch is already in normal position or when such selector is restored to normal position if it is at that time not at normal.

What is claimed is:—

1. In a telephone exchange system a plurality of automatically operable multiposition switches, an external control circuit, a quick-acting relay in said circuit, a slow-acting relay, controlled by said quick-acting relay, and a second quick-acting relay, said 105 quick-acting relays and said slow-acting relay cooperating to control the setting, changeover and restoration of said switches in accordance with circuit changes in said control circuit. 115

2. In a telephone exchange system a plurality of automatically operable multiposition switches, means for moving said switches in a forward direction, means for restoring said switches in the opposite direction, an external control circuit over which the setting, changeover and restoration to normal of said switches is controlled and a single slow-acting relay controlled by circuit changes in said circuit and controlling the restoration to normal of one of said switches and the changeover from one of said switches to the next to be operated. 120

3. In a telephone exchange system a control circuit, a plurality of automatically op- 125

erable multiposition switches adapted to be one after another brought into association with said circuit to be set by series of short impulses therein and a single slow-acting relay associated with said circuit responding to a prolonged closure thereof to produce the changeover from one of said switches to the next to be set, and responding to a prolonged interruption of said circuit to produce the restoration to normal of said switches.

4. In a telephone exchange system, a control circuit, a plurality of automatically operable multiposition switches adapted to be one after another brought into association

with said circuit to be set by series of short impulses therein, two quick-acting relays, one included in said circuit, directly controlling the setting of said switches, and a single slow-acting relay coöperating with said quick-acting relays and controlling the changeover from one of said switches to the next to be operated and the initiation of restoration of said switches to normal. 20

In witness whereof, I hereunto subscribe 25 my name this ninth day of July, A. D., 1914.

WILLIAM HUGO MATTHIES.
